UNITED STATES PATENT OFFICE

136,177

DESIGN FOR A BAKING PAN

Durries Crane, Chicago, Ill.

Application May 8, 1943, Serial No. 110,155

Term of patent 3½ years

To all whom it may concern:

Be it known that I, Durries Crane, a citizen of the United States, residing at Chicago, in the county of Cook, State of Illinois, have invented a new, original, and ornamental Design for a Baking Pan, of which the following is a specification, reference being had to the accompanying drawing, forming part thereof.

I claim:

The ornamental design for a baking pan, as shown.

DURRIES CRANE.
